Primary Examiner — Robin V Webster(74) *Attorney, Agent, or Firm* — Fitch, Even, Tabin & Flannery LLP**CLAIM**

We claim the ornamental design for an irrigation housing component, as shown and described.

DESCRIPTION

FIG. 1 is a top perspective view of an irrigation housing component showing our design;

FIG. 2 is a top view thereof;

FIG. 3 is a front view thereof;

FIG. 4 is a rear view thereof;

FIG. 5 is a left side thereof, the right side being a mirror image;

FIG. 6 is a bottom view thereof; and,

FIG. 7 is a bottom perspective view thereof.

The broken line showing is included for the purpose of illustrating and forms no part of the claimed design.

A portion of the drawings are shaded for color using the symbol in the tables of MPEP § 608.02 for the color "Violet or Purple." For portions of the drawings that are not shaded with such symbol, no specific color is claimed.
